(57) **CLAIM**

The ornamental design for a roll up door with wavy surface lath, as shown and described.

DESCRIPTION

FIG. 1 is a perspective view of a portion of a roll up door with wavy surface lath including six wavy surface laths according to the present design, it being understood that such door could include a different number of such laths;

FIG. 2 is a front view of the roll up door with wavy surface lath of FIG. 1;

FIG. 3 is a right side view of the roll up door with wavy surface lath of FIG. 1;

FIG. 4 is a left side view of the roll up door with wavy surface lath of FIG. 1;

FIG. 5 is a top view of the roll up door with wavy surface lath of FIG. 1;

FIG. 6 is a bottom view of the roll up door with wavy surface lath of FIG. 1; and,

FIG. 7 is a perspective view of one lath of the door of FIG. 1 showing the wavy surface.

The claimed design comprises the wavy surface elements shown in solid lines, the elements shown in dotted lines forming no part of the claimed design.

The claimed design is shown broken in the center with broken lines to indicate indeterminate length.
